BOTTLE CAPPER

Filed Feb. 8, 1928

FIG. 2

FIG. 4

INVENTOR.

Harry J. Lebherz,
BY John O Brady
ATTORNEY.

UNITED STATES PATENT OFFICE

HARRY J. LEBHERZ, OF FREDERICK, MARYLAND, ASSIGNOR TO THE EVEREDY COMPANY, OF FREDERICK, MARYLAND, A CORPORATION OF MARYLAND

BOTTLE CAPPER

Application filed February 8, 1928. Serial No. 252,826.

My invention relates broadly to bottle cappers and more particularly to a bottle capper of the manually controlled type.

One of the objects of my invention is to provide a bottle capper having a vertically extending rack and a slidable head where the head is adjustable to selected positions along the rack, with spring means for maintaining the head in an elevated position preparatory for capping operations, the spring means having a protective device for maintaining the setting of the capping head in a selected position with respect to the vertically extending rack.

Another object of my invention is to provide a construction of yoke or bridge member for the capping head of a bottle capping tool which yoke or bridge member is maintained under spring tension with respect to the operating lever of the bottle capper for maintaining the operating lever in a predetermined setting on the vertically extending rack of the bottle capping tool.

Still another object of my invention is to provide a construction of vertically extending rack and adjustable bottle capping head thereon, with spring means extending on each side of the bottle capping head and connecting to a bridge member protruding across the bottle capping head and affording that degree of pressure upon the operating lever of the bottle capping tool which will serve to maintain the operating lever in a particular setting with respect to the vertically extending rack.

A still further object of my invention is to provide a construction of yoke and bridge member for the bottle capping head of a bottle capping tool where the yoke is maintained by spring pressure in engagement with the head of the operating lever and extends along the operating lever to serve as a protecting means for preventing the displacement of the lever from a predetermined selected setting for performing bottle capping operations on a bottle of a particular size.

Other and further objects of my invention reside in the construction of yoke and guard member for the capping head of a bot-

tle capping tool as described more fully in the specification hereinafter following by reference to the accompanying drawings in which:

Figure 1 is a side elevation of the bottle capping tool showing the device of my invention applied thereto; Fig. 2 is a cross-sectional view through the bottle capping head on line 2—2 of Fig. 1 and showing the vertically extending rack in elevation; Fig. 3 is an enlarged view of the bottle capping head showing the arrangement of yoke and guard thereon; Fig. 4 is a view of the bottle capping head and the position assumed thereby when pressure is applied to the operating lever during bottle capping operations; and Fig. 5 is a perspective view of the yoke and guard for the bottle capping head constructed in accordance with my invention.

My invention relates to that class of bottle capping tools shown more particularly in copending application of Harry J. Lebherz, Serial No. 69,868, filed November 18, 1925, now Patent No. 1,681,144, dated August 14, 1928. The details of construction of the bottle capping tool of my invention are described more particularly in Letters Patent Nos. 1,356,161, dated October 19, 1920, granted to Harry J. Lebherz, Reissue 15,285, dated February 14, 1922, granted to Harry J. Lebherz, 1,421,698, dated July 4, 1922, granted to Harry J. Lebherz, 1,643,076, dated September 20, 1927, granted to Harry J. and Robert W. Lebherz, and 1,651,720, dated December 6, 1927, granted to Harry J. and Robert W. Lebherz.

Heretofore there has been a tendency for the operating handle to fly up at the end of each bottle capping operation and jump out of gear with the vertically extending rack of the bottle capper. The appliance of my invention prevents the operating lever from jumping out of gear with the vertically extending rack so that when the bottle capping head is set in a selected position the head will remain in that position for successive bottle capping operations. When the head is removed to different settings along the vertically extending rack and the handle is swung to an upright position all set for ad-

justing the capper head to a differently sized bottle, the yoke of my invention serves as a guard or shield to prevent the teeth on the rack from catching on the last tooth of the segment carried by the handle.

5 Referring to the drawings in detail, reference character 1 designates the base of the bottle capping tool from which the standard 2 extends. A rack 3 is provided on the extremity of the standard 2 having a row of rack teeth 4 over which the sliding member or adjustable head 5 is positioned. A capping throat 6 is secured to the capper head 5 in a position to serve as a pressure means for 10 forcing a crown cap over the head of a bottle mounted upon the supporting base 1. The hand lever 8 connects with a segment member 9 which is pivoted at 7 in the capper head 5. The teeth 10 of the segment member 9 mesh 15 with the rack teeth 4. The upper edge of the segment is notched as represented at 12 in a position corresponding to notches 11 formed in the sides of the capper head 5. The guard is represented at 14 as having a 20 rearwardly extending portion and contacting face at 20 for engaging the hand operating lever. The guard 14 has a bridge portion 16 and a pair of downwardly depending lugs 15. The guard is maintained in a position 25 transverse to the segment by springs 17 which connect at one end with hooks 18 pressed from the material of the walls of the capper head, and at the other end with the lugs 15 on the guard. The guard extends for a substantial 30 distance along the operating handle and maintains a sufficient downward pressure upon the operating handle to prevent the operating handle from jumping to a position where the segment might become disengaged with the rack. In this way the handle 35 is maintained in a particular setting with respect to the rack. The guard serves as a shield for preventing the teeth on the rack from catching on the last tooth on the operating lever when the operating lever is in its 40 upright position or set for adjusting the lever to differently sized bottles for the reason that the guard is always disposed between the lever and the rack when the lever is in raised position. 45 When the guard separates the teeth of the hand lever from the rack teeth, it is possible to move the capping head freely with respect to the rack to any selected position.

50 The construction of the guard has been 55 found to be extremely practical, and while I have described a preferred embodiment of my invention, I desire that it be understood that modifications may be made and that no limitations upon my invention are intended other than are imposed by the scope of the appended claims.

55 What I claim as new and desire to secure by Letters Patent of the United States is as follows:

1. In a bottle capper a vertically extending rack, a capping head, a hand operating lever journaled in said capping head and having a toothed segment thereon engageable with the teeth of said rack, spring members extending from opposite sides of said capping head and a bridge member connected at opposite sides to each of said spring members, said bridge member extending along said hand operating lever and providing an abutment at a point beyond the pivot thereof. 70

2. In a bottle capper a vertically extending rack, a capping head, a hand operating lever journaled in said capping head and having a toothed segment thereon engageable with the teeth of said rack, spring means connected to opposite sides of said capping head and a bridge member embracing the top of said capping head and depending on each side thereof to points of connection with said spring means, and a laterally extending portion on said bridge member abutting with said hand operating lever at a point beyond the pivot thereof for limiting the upward movement of said lever. 80

3. A bottle capping tool comprising a vertically extending rack, a head adjustable vertically along said rack, a hand operating lever journaled in said head, a segment on one end of said hand operating lever meshing with said rack, a pair of spring members connected to opposite sides of said head and terminating in hooks on opposite sides of the upper extremity of said head and a strip member having a pair of downwardly extending lugs 90 connected to the hook extremities on said spring members for continuously urging said segment downwardly with respect to said head, said strip member extending along said lever for limiting the upward movement 100 of said lever. 95

4. In a bottle capping tool a vertically extending rack, a head slideable on said rack, a hand operating lever journaled in said head and having a segment thereon meshing with said rack, spring devices positioned on opposite sides of said head, a strip member having a pair of lugs extending therefrom on opposite sides of said head and connected with the ends of said spring devices, said strip member extending along said hand operating lever and contacting therewith at a point beyond the pivot thereof for limiting the upward movement of said lever. 110

5. In a bottle capper, a rack, a bottle capping head slideable thereon, an operating lever journaled in said head and meshing with said rack for shifting said head along said rack, a pair of spring members connected to opposite sides of said head, a bridge member extending across said head, said bridge member having an integrally extending lug protruding downwardly on each side of said head and connected with each of the spring mem- 120

bers, and an extension formed on said bridge member, said extension having the end thereof curved upwardly and forming a tangential contact with said operating lever at a point beyond the fulcrum thereof for limiting the upward movement of said lever.

5 In testimony whereof I affix my signature.

HARRY L. LEBHERZ.
